Original application October 5, 1934, Serial No.
747,070. Divided and this application June 29,
1938, Serial No. 216,423

4 Claims. (Cl. 178—7.1)

This invention relates to amplifiers for combining and amplifying a plurality of signals including signal components having frequencies aggregating a wide frequency band.

5 This application is a division of applicant's pending application, Serial No. 747,070, filed October 5, 1934.

It is an object of the present invention to provide an improved amplifier for combining and 10 amplifying a plurality of signals, which may comprise television signal components, including frequencies aggregating a wide frequency band, for developing a resultant signal representing the sum of the combined signals.

15 In accordance with the present invention, there is provided an amplifier which comprises a plurality of vacuum tubes. Means are provided for individually applying to the input electrodes of the several tubes a plurality of signals, which 20 may represent television signal components, including frequencies aggregating a wide frequency band. A common output circuit is provided for all of the tubes comprising an electric wave filter having a uniform impedance over the wide frequency band. The output impedance of the filter 25 is of a value which is low relative to the anode-cathode impedance of each of the tubes. With this arrangement, the signal voltage developed across the common output filter impedance by 30 each of the tubes is substantially independent of, and unaffected by, variations of the impedances of the other tubes. Therefore, the instantaneous voltage developed across the output filter impedance is the sum of the instantaneous signal 35 output voltages of all of the tubes.

For a better understanding of the present invention, together with other and further objects thereof, reference is had to the following description taken in connection with the accompanying drawing, and its scope will be pointed out in the appended claims.

The single figure of drawing is a circuit diagram of a television transmitter including a combining amplifier embodying the present invention.

45 Referring now more particularly to the system of the single figure of the drawing, the system there illustrated comprises a complete television transmitter including circuits for generating the television modulated-carrier wave and applying it to the antenna, the essential units comprising 50 a master oscillator 4, a harmonic generator 5, a radio-frequency amplifier 6, a balanced modulator 7, a radio-frequency power amplifier 8, a transmission line 9, and an antenna system 10 connected in cascade, in the order named.

For the purpose of combining and amplifying component modulation-frequency voltages representing the various components of the television signal, there is provided an amplifier system comprising five vacuum-tube amplifiers 67, 68, 69, 70, and 71, each having a separate component modulation-frequency band supplied to its input. The output circuits of these several tubes have in common as their load circuit a low-pass filter unit composed of series inductance arm 10 73, shunt condenser arms 76 and 77 and terminating resistors 74 and 75. This filter develops and transmits signals of all frequencies from 24-813,000 cycles to the grid circuit of a vacuum-tube repeater 72 via condenser 78 and potentiometer 79. The shunt condensers 76 and 77 represent or include the output tube capacitances of vacuum tubes 67, 68, 69, 70, and 71 and the input capacitance of the following tube 72. For the wide frequency band to be passed, the mentioned inherent tube capacitances alone generally suffice for elements 76 and 77 without the necessity for supplemental physical condensers. Since the branch 78, 79 excludes direct current, the susceptance of condenser 78 is made large 25 compared with the conductance of resistor 79 to ensure passing without attenuation all frequencies as low as the picture frequency of 24 cycles per second. If the anode-cathode impedance of each of the several tubes 67-71, inclusive, is high compared with that of the filter, as is the case if tubes of the pentode type are used, as shown, the signal voltage developed 30 across the filter and passed on to the input of tube 72 will be practically the sum of the instantaneous signal outputs of the several tubes. 35

The output circuit of tube 72 extends to a low-pass filter comprising a series inductance arm 80, shunt condenser arms 83 and 84, and terminating resistors 81 and 82. This filter is in the common anode supply circuit to tube 72 and the balanced tube arrangement of modulator 7. The modulation-frequency voltages developed by the tube 72 across this filter are, therefore, applied in like phase to the anodes of the tubes of 45 the modulator 7. In effect, the signal voltage across output terminating resistor 82 aids or opposes the anode voltage supply of the modulator 7 in accordance with the instantaneous values of the modulation-frequency signals. For 50 this type of modulation, the adjustments of the modulator 7 are made such that the radio-frequency output of the modulator 7, as applied to the input of the amplifier 8, varies linearly with the anode voltage and, hence, the amplitude of 55

carrier-frequency voltage applied to the amplifier 8 is caused to vary directly as the modulation voltage output of the amplifier 72. The filter 80-84 is designed, in a manner understood, to simulate a pure resistance to the extent that all frequencies within its pass band (as 24-813,000 cycles) are equally attenuated. Additionally, the design is such that the phase shift varies linearly with frequency. Thus the output voltage wave form is a replica of the input wave form. Likewise the action is similar to that of a resistance-coupled amplifier at low frequencies, in that the signal wave form as applied to the input of tube 72 and as developed at the associated low-pass filter output is oppositely poled.

In order to produce a "negatively" modulated wave, including "negatively" modulated synchronizing-impulse peaks, the signal output of the amplifier 72 must be a positive maximum when black in the picture or the synchronizing-impulse peaks are to be represented. Conversely, the synchronizing-impulse peaks and the polarity of the signal representing black in the picture are represented by maximum negative as applied to the grid of the tube 72. This requires positive poling at the grids of tubes 67, 68, and 69.

For generating the several component frequency bands of the modulation frequencies, five circuit sections are required. The top section starts with a photocell 56 which is provided with a unidirectional voltage source 57 and a load in the form of a low-pass filter unit 85 having a cutoff frequency at 800,000 cycles. The photocell 56 represents a source of video-frequency signals which, in the well-known manner, vary in accordance with the values of light in successive elemental areas of a scene to be transmitted. For example, the photocell may be employed in a conventional mechanical scanning system, in which a scanning light beam is focused on the photocell to develop the video-frequency signals, including a source of light focused in a horizontal line and passing through a vertically moving film carrying the scenes, with a rotary mirror-drum and mask arrangement operating to focus successive points of the horizontal line on the photocell. With the filter 85 properly designed, its inductance tunes with the input and output capacitances in series to give a resonant peak near the upper frequency cutoff and thus to raise the gain at the high-frequency end of the band. The employment of properly chosen terminating resistances then acts to level the response curve of the filter to give a uniform response up to the cutoff frequency. The shunt capacitances of the filter 85, as illustrated, need not be actual condensers but may be considered to include or be composed entirely of the inherent tube capacitances. By designing the filter to utilize the tube capacitances in this way, much greater uniformity in gain over the band can be obtained.

The output voltage of the filter 85 is applied to two amplifiers: the one, including tubes 88 and 90, constituting a vision-frequency amplifier of 24-800,000 cycles and the other, including tubes 94 and 95, serving as the direct current (that is, 0-24 cycles) background-illumination amplifier. The voltage as applied to the input of tube 88 is via a blocking condenser 86 and a grid-leak resistor 87. The condenser 86 is chosen to have a large capacitance so that its reactance at the lowest frequency, 24 cycles, is small compared with the resistance of resistor 87 (that is, a low time constant is employed) and so that all frequencies in the band 24-800,000 cycles are applied

effectively without attenuation to the input of the tube 88. The coupling filter 89, tube 90, and its output filter 91 complete the system for applying the vision-frequency components, amplified and undistorted, via the condenser 92 and potentiometer 93 to the grid of the amplifier tube 67. Adjustment of the potentiometer 93 serves to set the level of modulation as far as the vision-frequency components are concerned.

The poling of battery 57 is such that, when light strikes on photocell 56, the voltage drop across the filter 85 is applied negatively to the control grid of the tube 88. Simultaneously, the grid of the tube 90 becomes more positive and the grid of the tube 67 becomes more negative. This is the proper poling (when followed on through tube 72 to modulator 1 as previously described) to cause the carrier-wave amplitude to decrease. Darkness at photocell 56, conversely, causes an increase in amplitude of the carrier wave. Hence, the poling shown is such as to give "negative" modulation of the carrier wave by the vision-frequency components.

The voltage output of filter 85 is also applied to the grid of the tube 94 which with tube 95 and interstage coupling resistor 96 operate as a direct current amplifier to develop across resistor 98 in the output circuit of tube 95 a voltage proportional to the general background illumination of the picture. Condensers 97 and 99 shunting resistors 96 and 98, respectively, prevent the development of voltage of higher frequencies since only 0-24 cycles need be passed by this amplifier.

Unit 17 is an intermediate-frequency generator for exciting the grid of a modulator tube 100. The space current circuit from the battery to the anode of tube 100 has in series with it the resistor 98 across which the background-illumination potentials are developed. The intermediate-frequency carrier wave is applied by tube 100 to the input circuit 102, 103 of the amplifier tube 70 through a tuned transformer 101. The modulator tube 100 is adjusted so that the carrier-wave amplitude, as applied to the grid of the amplifier 70, varies directly as the anode voltage of tube 100. Thus the carrier-wave amplitude varies directly with the background-illumination voltages developed across resistor 98. The poling is such that darkness on photocell 56 results in an increase in the carrier amplitude to provide "negative" modulation of the carrier wave. The amplitude of the background-illumination modulated intermediate-frequency carrier wave applied to the grid of the amplifier 70 to modulate the transmission carrier wave is set by adjustment of potentiometer 103.

The arrangement of the channel for audio-frequency modulation component is, briefly, like that for the background-illumination component. A photocell 64 is operated by light varying in accordance with the sound signal to be transmitted, as by a sound record on film, and develops corresponding audio-frequency voltages across a resistor 104 in its output circuit for application to an amplifier tube 105. Unit 21 is an intermediate-frequency carrier-wave generator (807,000 cycles) for exciting the grid of modulator tube 107. The output of tube 105 is coupled by low-pass filter 106 (having a cutoff at 6000 cycles to develop the audio-frequency band of 50-6000 cycles, approximately) to the anode of modulator 107. The resulting sound-modulated carrier is applied to the grid circuit of amplifier tube 71 through a transformer 108 tuned to the intermediate frequency.

The line-frequency impulse generator comprises a voltage source 109 which charges a condenser 110 through a constant current tube 111. A short-circuiting tube 112, including a resistor 114 in its output circuit and regenerated by a tube 113 including a resistor 115 in its load circuit, serves rapidly to discharge the condenser 110 whenever a predetermined voltage across the condenser 110 has been reached. The voltage across the condenser 110 is of saw-tooth wave form, while the current through the condenser 110 and anode-cathode circuit of the short-circuiting tube 112 is of impulse wave form. Hence, the voltage across the resistor 114 is also of impulse wave form, the peaks being poled negative with respect to ground, and the voltage across resistor 115 in the output circuit of the feed-back or reversing tube 113 is likewise of impulse wave form, the impulse peaks being oppositely poled, that is, positive relative to ground. The line-frequency impulse peaks developed across the resistor 115 are applied to the control grid of the amplifier 68 in amplitude set by a potentiometer 116 so that the grid of the amplifier 68 is highly positive during each line-frequency impulse peak. By following this transmission through to its effect on modulator 7, it will be clear that the carrier-wave amplitude is increased to represent each line-frequency impulse peak and to provide, according to definition, "negative" impulse modulation at the line frequency. The setting of the frequency of the line-frequency impulse to its approximate value is made by adjusting the bias on the control grid of tube 111.

The generator 65 is a source of voltage of line frequency as determined by the scanning mechanism and this voltage is applied to the grid of shorting tube 112, via a resistor-condenser connection, to pull into step and hold in synchronism, at the correct line frequency, the impulse generator. The phase or timing of the line-frequency impulses can be controlled so that they coincide with the initiation of the line-scanning intervals by setting the bias of the grid of tube 111. In practice, the control voltage from the synchronizing unit 65 holds the impulse generator in synchronism over a wide range of bias adjustments on the grid of the charging tube 111 so that considerable phase control to provide coincidence of line-frequency impulses and initiation of the line-scanning interval can be had in this way.

The picture-frequency impulse generator is illustrated as entirely similar to that just described for the line-frequency generator. The constants of the circuit are chosen for efficient generation of the lower frequency of 24 cycles. The elements are, therefore, similarly numbered, the numbers being primed. The control of the impulse generator is by the synchronizing generator 66 and the poling is such that "negative" impulse modulation of the carrier wave results. The amplitude of the impulse as impressed on amplifier 69, that is, the control of the percentage modulation, is set by adjustment of a potentiometer 117.

The several amplifiers 67, 68, 69, 70, and 71 are designed and operated as linear amplifiers. Since amplifiers 68 and 69 are repeaters of impulse wave forms which in each case are applied with positive poling of the impulse peaks to their control grids, these amplifiers are preferably operated with large negative control-grid biases. The amplifier 72 must likewise be carefully designed to prevent overload, especially where the instantaneous values of line-frequency and pic-

ture-frequency impulse peaks add to produce a maximum negative signal on the grid of the tube 72. Similarly, modulator 7, if it is to follow faithfully the modulation-frequency components, must be designed and adjusted so that the amplitude of the carrier wave developed in its output circuit increases linearly with the modulation voltage applied from the amplifier 72, even during the interval in which the line- and picture-impulse peaks add to give the maximum increase in carrier amplitude. The bias adjustment of the amplifier 72 may be made such that it is a linear amplifier for all voltages applied to its grid up to a predetermined negative maximum equal to the amplitude of a line- or picture-impulse peak. For such adjustment, the amplifier 72 will overload to suppress any line-impulse peaks which ride above the picture-impulse peak.

While there has been described what is at present considered to be the preferred embodiment of this invention, it will be obvious to those skilled in the art that various changes and modifications may be made therein without departing from the invention, and it is, therefore, aimed in the appended claims to cover all such changes and modifications as fall within the true spirit and scope of the invention.

What is claimed is:

1. In a television system, a combining amplifier comprising a first signal-translating channel including a vacuum tube, means for applying to the input electrode of said tube a signal voltage representing a component of a television signal aggregating a wide frequency band, a second signal-translating channel including a vacuum tube, means for applying to the input electrode of said last-mentioned tube a signal voltage representing a component of a television signal aggregating a wide frequency band, a common output circuit for both of said tubes comprising an electric wave filter having a substantially uniform impedance at all frequencies in said wide bands, said tubes being connected in parallel across said common output circuit, said impedance being of a value which is low relative to the anode-cathode impedance of each of said tubes, whereby the voltage developed across said impedance by each of said tubes is substantially independent of, and unaffected by, variations of the impedances of said tubes and whereby the instantaneous voltage developed across said output impedance is the sum of the instantaneous voltage outputs of both of said tubes.

2. In a television system, a combining amplifier for separately amplifying and combining voltages representing components of a television signal having frequencies aggregating a wide frequency band, comprising a plurality of vacuum tubes, means for applying said voltages to the input electrodes of said tubes, a common output circuit for all of said tubes comprising an electric wave filter having a substantially uniform impedance at all frequencies in said wide band, said tubes being connected in parallel across said common output circuit, said impedance being of a value which is low relative to the anode-cathode impedance of each of said tubes, whereby the voltage developed across said impedance by each of said tubes is substantially independent of, and unaffected by, variations of the impedances of said tubes and whereby the instantaneous voltage developed across said output impedance is the sum of the instantaneous voltage outputs of all of said tubes.

3. In a television system, a combining amplifier for combining and amplifying voltages from a plurality of sources and representing components of a television signal having frequencies aggregating a wide frequency band, comprising a plurality of vacuum tubes having separate input circuits for individually applying said voltages thereto, and a common output circuit for all of said tubes comprising an electric wave filter having a uniform output impedance for all frequencies in said wide band, said tubes being connected in parallel across said common output circuit, said impedance being of a value which is low relative to the anode-cathode impedance of each of said tubes, whereby the voltage developed across said impedance by each of said tubes is substantially independent of, and unaffected by, variations of the impedances of said tubes and whereby the instantaneous voltage developed across said output impedance is the sum of the instantaneous voltage outputs of all of said tubes.

4. In a television system, an amplifier for combining and amplifying voltages from a plurality of sources, said voltages representing

components of a television signal and having frequencies aggregating a wide frequency band, comprising a plurality of vacuum tubes of the multigrid type each including an anode, a cathode, a control grid, and a screen grid, an input circuit for each of said tubes, means for applying said voltages individually to said input circuits, an output load circuit common to the anode-cathode elements of all of said tubes, said anode-cathode elements being connected in parallel across said common output circuit, said output circuit comprising a filter structure to provide a substantially uniform impedance at frequencies throughout said wide band, and means for applying unidirectional operating potentials to the elements of said tubes to adjust the anode-cathode impedance of each of said tubes to a high value relative to said impedance of said output circuit, whereby the instantaneous value of the voltage developed across said output circuit varies in accordance with the instantaneous sum of the several input voltages.
